CLAIM

The ornamental design for a shower spray deflector unit, as shown and described.

DESCRIPTION

FIG. 1 is a left side elevational view of a shower spray deflector unit showing my new design;
FIG. 2 is a right side elevational view thereof;
FIG. 3 is a top plan view thereof;
FIG. 4 is a bottom plan view thereof;
FIG. 5 is a front elevational view thereof; and,
FIG. 6 is a rear elevational view thereof.
